FOREIGN PATENT DOCUMENTS

RU 00100158 * 10/2016

Primary Examiner — Brett Miller*Assistant Examiner* — Rani J Abdallah(74) *Attorney, Agent, or Firm* — N.V. Nederlandsch Octrooibureau(57) **CLAIM**

The ornamental design for a bottle, as shown and described.

DESCRIPTION

FIG. 1 is a front perspective view from the top and right side of a bottle showing our new design;

FIG. 2 is a an elevational view of the front side thereof;

FIG. 3 is a an elevational view of the back side thereof;

FIG. 4 is an elevational view of the left side thereof;

FIG. 5 is an elevational view of the right side thereof;

FIG. 6 is a top plan view thereof; and,

FIG. 7 is a bottom plan view thereof.

All broken lines are directed to environment and are for illustrative purposes only; the broken lines form no part of the claimed design.

1 Claim, 5 Drawing Sheets(56)
